G. Warren Wright,
ATTORNEY

UNITED STATES PATENT OFFICE.

ROBERT HELMER, OF NEW YORK, N. Y.

FILING DEVICE.

1,073,854.

Specification of Letters Patent. Patented Sept. 23, 1913.

Application filed February 14, 1912. Serial No. 677,437.

To all whom it may concern:

Be it known that I, ROBERT HELMER, a citizen of the United States, residing at New York city, in the county and State of New York, have invented certain new and useful Improvements in Filing Devices, of which the following is a clear, full, and exact description.

The object of this invention is to provide an improved filing device for filing drawings and papers in racks, so that the papers or drawings will hang vertically.

In carrying out the invention, I provide a set of tracks, between two of which there may be slid a set of drawings bound together at one end in a metal tube of curved or elliptical general cross section. I preferably provide a cabinet, to the under side of the top of which I locate a number of tracks parallel one with the other, each track formed of metal of an inverted U cross section, the arms of the U slanting slightly away from the center. These U shaped cross section drawings I mount a short distance from the top of the cabinet on suitable distancing sleeves by means of screws passing through the tracks, and through the sleeves. The drawings I secure to the inside of an elliptical tube open at its bottom edge, and provided with a depending flat flange, through which suitable slots are provided, so that a fastener of the usual variety may pass through the slots and through the drawings, thus securing the same with their upper ends within the elliptical sleeve. The thickness at the center or short diameter of this sleeve is such that it will ride nicely between two adjacent tracks, so that the entire set of drawings in a given tube may be readily slid into place and taken out.

The scope of my invention will be pointed out in the claims.

In the drawings, Figure 1 is a perspective view of a cabinet provided with my improved invention. Fig. 2 is an end elevation showing two tracks and the upper part of a map holder drawn to an enlarged scale from that shown in Fig. 1. Fig. 3 is a side elevation of Fig. 1 with part broken away. Fig. 4 is a bottom plan of Fig. 3.

As shown in the drawing, 1 is the cabinet to the top of which on the under side thereof I fasten a series of parallel tracks 3 at a distance from the top thereof. These tracks 3 are of the cross section shown in Fig. 2, 55 being an inverted U with the sides slanting away from the center, except at the front end, where the sides are pressed together so as to be parallel, and to present a wider opening at the front than throughout the 60 length. These inverted U tracks 3 are secured to the top of the cabinet 2 by means of screws 4 passing through the center of the tracks, and through distancing bushings 5 so that all the tracks, not only will be 65 parallel, but will be an even distance from the under side of the top of the cabinet.

The maps or drawings 6 are collected in sets and punched at a distance from their binding edge to receive a fastener 7. The 70 binding tube 8, preferably of metal, and elliptical in shape with its lower end open, and having an extending flat leaf 9, is also provided with punched holes 10 at suitable distances. The drawings are inserted as 75 shown in Fig. 2 into the elliptical tube, and the fastener 7 passed through the slots or holes 10 in the leaf 9, through a washer, and also through the drawings, and are bent over as shown clearly in Fig. 4. When the 80 drawings are thus assembled they may be readily moved in and out along the tracks formed by the inverted U shaped rails.

The ends of the elliptical tubes 8 may be provided as shown in Figs. 3 and 4 with 85 knobs 11, which may be made to fit the tube and projections 12 at the end thereof bent over to grasp the same.

I claim as my invention:

1. As an article of manufacture a supporting track for a filing device comprising a strip of sheet metal turned down at its longitudinal edges to provide a pair of depending flanges to the strip, said flanges being diverged toward their free edges whereby to provide oppositely inclined supporting faces at either side of the strip, said flanges converging at the forward end of the strip whereby to provide inclined guiding faces merging into said supporting faces. 95 100

2. In a filing device, the combination with
a support, and a plurality of sheet binding
tubes, of a plurality of sheet metal tracks of
substantially inverted V-shape, and means
5 depending a short distance from the under-
side of the support to which said tracks are
secured for holding said tracks in parallel
and spaced relation whereby to provide

spaces between the tracks for the reception
of said tubes.

Signed at New York city, New York, this
13th day of February, 1912.

ROBERT HELMER.
